UNITED STATES PATENT OFFICE.

ANDREW J. RITTER, OF RAHWAY, NEW JERSEY.

INCLINED-PLANE PENDULUM-POWER.

SPECIFICATION forming part of Letters Patent No. 370,820, dated October 4, 1887.

Application filed October 9, 1886. Serial No. 215,807. (Model.)

To all whom it may concern:

Be it known that I, ANDREW J. RITTER, a citizen of the United States, residing at Rahway, in the county of Union and State of New Jersey, have invented certain new and useful Improvements in Graduated - Incline Pendulum-Power; of which the following is a description.

My invention relates to an improvement in which a two-armed movable pendulum operates in conjunction with an incline bar placed upon trusses or otherwise.

The object of the improvement is to convey or propel various articles, useful or novel, by gradual incline and pendulum motive power, the same being applied to moving toys, working clocks, carrying weight down inclines, &c. To attain this object I combine the two parts, Figures 1 and 2, as illustrated in the accompanying drawings.

The same letters and figures refer to the same parts.

I construct my incline bar A, also my double-armed pendulum B, of any material suitable for the purpose. I suspend my double-armed pendulum B with bearing-pins, as at E E, or with side bearing-rods, as at Fig. 3, or with cross bar or plate, as at Fig. 4, or any form adapted to the purpose.

B, Fig. 1, shows the movable double armed pendulum with bearing-pins E E.

A, Fig. 2, shows the incline bar with a declining grade of about one and half inch to the foot, which is held in position by means of the suspending-rods D D, the same being attached to trusses C C or otherwise.

To start the pendulum B on its graduating motion down the incline, place it upon the elevated end of the bar A and give it a slight oscillating motion, the same as would be given to start the pendulum of an ordinary clock. This causes the side arms at F F of the pendulum B to strike the sides of the incline bar A, the rebound of which throws the opposite arm of the pendulum B forward and down the incline A, the bearing-pins E E at the same time catching on the incline bar A and graduating step by step the oscillating and forward motion of the pendulum B down to the end. It will naturally suggest of itself, without any further explanation, that if the incline A is reversed the pendulum B will travel back to the place of starting.

I do not confine myself to any particular form for the two-armed pendulum B or the bearings E E, nor do I claim any particular means for holding or supporting the incline bar A.

What I do claim as my invention is—

The graduated pendulum-power described, comprising an inclined support and device, substantially as set forth herein, provided with inwardly-projecting means for loosely engaging said inclined support, whereby on imparting a slight motion to said device it is caused to oscillatingly, by a step-by-step movement, descend the incline, substantially as set forth.

ANDREW J. RITTER.
